UNITED STATES PATENT OFFICE.

JOHN W. MAY, OF BOSTON, MASSACHUSETTS, ASSIGNEE OF ONE-EIGHTH TO J.
DUDLEY CLARK, OF BOSTON, MASSACHUSETTS.

DEVICE FOR UNLOCKING LASTS.

Application filed August 6, 1921, Serial No. 490,202. Renewed October 28, 1924.

To all whom it may concern:

Be it known that I, JOHN W. MAY, a citizen of the United States, and resident of Boston, county of Suffolk, State of Massachusetts, have invented an Improvement in Devices for Unlocking Lasts, of which the following description, in connection with the accompanying drawing, is a specification, like characters on the drawing representing like parts.

In my co-pending application, Serial No. 287,681, April 5, 1919, I have shown and described a collapsible last comprising a fore part, a heel part, and wedge-shaped intermediate part movable transversely of the last and by its movement in one direction operating to extend the last and a locking device for locking the intermediate member to the heel part when the last is extended, thereby holding the last in such extended condition. The last described in said application also has a lock-releasing member carried by the heel part and situated exterior to, but operable from within the thimble in the heel part, thereby to unlock the last in order that it may be contracted or collapsed.

The purpose of placing the lock-releasing member exterior to the thimble is so that the placing of the last on an ordinary last pin will not in any way affect the lock.

It is the object of my invention to provide a novel device or implement for actuating said lock-releasing member. Said device or implement is in the form of a last pin adapted to enter the thimble of the last, and means actuated by the movement of the last necessary to insert the last pin into the thimble to actuate the lock-releasing member thereby to release the lock. With this device, therefore, the releasing of the lock involves simply inserting the last pin into the thimble, this operation resulting in automatically actuating the lock-releasing member.

In order to give an understanding of my invention I have illustrated in the drawings a selected embodiment thereof, which will now be described after which the novel features will be pointed out in the appended claims.

Fig. 1 of the drawings is a view in section showing one embodiment of my device for unlocking lasts, said view indicating the method of operation.

Fig. 2 is a view showing the implement in its normal position.

Before describing the construction of the last unlocking device I will refer briefly to the type of last with which said device is intended to operate. The last, shown generally at 1, is of that type comprising a fore part 2, a heel part 3, a wedge-shaped intermediate part 4 movable transversely of the last, and a telescopic connection 5 between the fore part and the heel part, which is constructed to hold said fore part and heel part in correct alignment but which permits them to move toward and from each other as the wedge-shaped intermediate part 4 is moved transversely. The last is also provided with a lock in the form of a spring-pressed latch 6 carried by the intermediate part and adapted to engage a keeper 7 carried by the heel part thereby to lock the latch in the extended position shown in the drawings. The latch is released from the keeper by means of a lock-releasing member 8 which is slidable in a passage 9 formed in the heel part, and which is situated entirely outside of the usual thimble 10 which is inserted in the heel part. The thimble 10 is provided with an opening 11 in one side in line with the passage 9 to permit a suitable implement to be inserted into the thimble and through said opening to move the lock-releasing member to the right Fig. 1 and cause it to force the latch 6 backwardly thereby to unlock the last.

The parts thus far described and their method of operation are fully set forth in my aforesaid co-pending application No. 287,681, and need not be repeated here.

As stated above the object of my present invention is to provide an implement by which the lock-releasing member 8 can be readily actuated whenever it is desired to unlock the last. Said implement device is in the form of a last pin adapted to be inserted into the thimble 10, and it has such a construction that the operation of inserting it into the thimble will cause the latch-releasing member 8 to be moved forwardly thereby to release the latch 6.

Such last pin is indicated at 12 and it may conveniently be supported in a suitable stand 13. The last pin is provided in one side with a groove 14 extending longitudinally thereof, in which is received a pusher

element 15 in the form of a lever that is pivoted at 16. This lever is slightly curved and is provided with the nose 17 and with the heel portion 18, the curvature and shape 5 of said lever being such that when it is turned so that the nose 17 is received entirely within the slot 14, the heel portion 18 will project beyond the slot, while when it is turned so that the heel portion is within 10 the slot, the nose portion 17 is projected beyond the slot. The heel 18 of the lever is acted on by a spring 19 which normally tends to swing said element into the position shown in Fig. 2 wherein the nose is withdrawn into the slot and the heel projects 15 beyond the periphery of the last pin.

The lever is so proportioned relative to the length of the thimble, and is so situated on the last pin that when the last pin is inserted into the thimble the end of the thimble will engage the heel 18 when the opening 11 in the thimble is opposite the nose 17. The engagement of the end of the thimble with the heel 18 will swing the lever 20 from the position shown in Fig. 2 to that shown in Fig. 1, thereby causing the nose 17 to be carried through the opening 11 in the thimble and against the latch-releasing member 8, such movement operating to 25 move the latch-releasing member 8 into the position shown in Fig. 1. The movement of the latch-releasing member 8 into this position forces the latch 6 backwardly and unlocks the latch, thus allowing the wedge-shaped intermediate member to move laterally into dotted line position, such movement of the intermediate member permitting the toe part to move backwardly to 30 toward the heel part.

With this invention therefore the unlocking of the latch involves simply the operation of placing the last over the last pin; such movement operating automatically to 40 actuate the lever to thereby release the lock.

Since the lock-releasing member 8 is situ-

ated outside the thimble, the placing of the last on an ordinary last pin will not, in any way, affect the lock.

I claim:

1. In a device for unlocking lasts wherein the lock is releasable by a lock-releasing member situated exterior to the thimble in the heel part, but operable from within said thimble, the combination with a last pin to 50 enter said thimble, of means carried by the last pin and actuated by the movement involved in placing the last over the last pin to actuate the lock-releasing member, thereby to unlock the last.

2. In a device for unlocking lasts wherein the lock is releasable by a lock-releasing member situated exterior to the thimble in the heel part, but operable from within said thimble, the combination with a last pin 55 constructed to enter said thimble, of means actuated by said thimble as it is inserted over the last pin to actuate the lock-releasing member, thereby to unlock the last.

3. In a device for unlocking lasts wherein the lock is releasable by a lock-releasing member situated exterior to the thimble in the heel part, but operable from within said thimble, the combination with a last pin 70 constructed to enter said thimble, of a member carried by the last pin and actuated by the thimble as it is placed over said pin to actuate the lock-releasing member.

4. In a device for unlocking lasts wherein the lock is releasable by a lock-releasing member situated exterior to the thimble in the heel part, but operable from within said thimble, the combination with a last pin 75 constructed to enter said thimble, of a member pivoted to the last pin and actuated by the thimble as it is placed over said pin to move the lock-releasing member, thereby to unlock the last.

In testimony whereof, I have signed my name to this specification.

JOHN W. MAY.
